WINDING-MACHINE.

1,163,037.

Specification of Letters Patent.

Patented Dec. 7, 1915.

Application filed April 8, 1914. Serial No. 830,441.

To all whom it may concern:

Be it known that we, FESTUS S. RAND and GEORGE N. TAYLOR, citizens of the United States, residing at Providence and East Providence, respectively, in the county of Providence and State of Rhode Island, have jointly invented certain new and useful Improvements in Winding-Machines, of which the following is a specification.

10 Our invention consists of improvements in winding machines and relates particularly to "friction" or "drum" winders in which the yarn-cop or thread-package is rotated through contact of its surface with a drive-roll or drum; and the yarn or thread is laid in place by a traversing thread-guide reciprocated in a path opposite the winding-spindle.

15 The object of our present improvement is to provide means for controlling the ratio of speed between the drive-roll and thread-guide to effect a differential change therein, whereby the method of depositing the coils of yarn in place on the cop will result in 20 more uniform and perfect winding as more fully explained hereinafter.

Our invention also contemplates other features of improvement as later explained.

25 The manner and means for carrying out our improvements are fully described in the following specification, illustrated by the accompanying drawings, in which like reference characters designate like parts.

30 In the drawings:—Figure 1 is a side elevation of our improved machine; Fig. 2 is an end view of the same, part sectional on the line X—X of Fig. 1, looking in the direction indicated by the arrow α ; Fig. 3 is a detail view of the driving-connections of 35 the machine showing the gear-casings in section to illustrate the mechanism contained therein; and Fig. 4 is a view in detail of the differential speed-changing device with the parts shown in a different position from 40 that illustrated in Fig. 1.

45 Referring first to Figs. 1 and 2, B designates the main frame of the machine which is provided with bearings for two horizontal shafts C and D.

50 On the lower shaft C is fixedly mounted a usual form of traverse-cam C' adapted to reciprocate the traversing thread-guide E; while fast on the upper shaft D is the drive-roll or drum D' from which the cop

is driven. The winding-spindle G, which is 55 adapted to receive the cop-tube α or other shell or holder on which the package is wound, is supported to rotate in an end bearing h mounted on a sliding carriage H. The carriage H is formed with two bearings 60 h' , h' fitted to slide on the vertical column or rod H' which extends upwardly from the frame B. Preferably, the spindle-bearing h is hinged on the carriage H by means of one or more pivoted arms h^2 , see Fig. 2, so as to 65 support the spindle G to normally maintain the cop directly above the driving-drum D' and in contact therewith during the winding. The arrangement of these parts is described more in detail in our previous application, Serial No. 824,490, filed March 13, 1914, and will not be further explained herein, it being sufficient to state that a usual hand-lever I is employed for operating the spindle-bearing manually, and suitable detent-means are provided for automatically controlling the position of the spindle in 70 relation to the drive-roll to maintain or arrest the operation of winding the yarn thereon.

75 The thread-guide E which traverses the yarn on the winding-spindle G is mounted on a carriage E' which slides on two horizontal rods e , e extending between the sides of the frame B, see Fig. 2. Connected with 80 the carriage E' is a cross-head f which slides in grooves f' , f' formed in the parallel sides of a traverse-frame F. On the under side of the cross-head f is a roll or stud c which engages the groove c' in the cam C' as shown 85 more particularly in Fig. 1. The frame F is formed with two legs f^2 , f^2 straddling the cam C' and pivotally mounted on the cam-shaft C. The frame F may be held fast 90 with the frame B as described in our application for patent previously referred to or, if desired, may be continuously oscillated about the axis of the cam-shaft C to intermittently shift the cam-roll c in the cam-groove c' . The purpose of this latter arrangement is to break up or prevent what is known as "ribbon-wind" on the surface of 95 the cop as fully explained in our previous application, Serial No. 813,013, filed Jan. 19, 1914. This feature of the machine, however, is not essential to the present invention and will not therefore be enlarged upon 100 herein.

It is the usual practice to arrange a plurality of winders in a series or "gang", all mounted on a common bed or table and for this reason we prefer to adapt the present machine to be driven from a single, main driving-shaft. As shown more particularly in Fig. 3, the driving-shaft J extends between the shafts C and D at right-angles thereto and is connected to drive the shaft

- 10 D by any suitable means such as pulleys or gears. Preferably, the shaft J carries a spiral-gear K meshing with a similar gear K' on the shaft D. Mounted on the end of the shaft D is a cone-pulley L from which 15 rotation is transmitted to an oppositely-arranged cone-pulley M by means of the usual driving-belt l. The pulley M is mounted fast on a shaft m which is rotatable in a bearing n formed as a part of a gear-casing 20 N. The casing N is mounted on the end of the cam-shaft C and incloses a gear O fast on said shaft and arranged to mesh with a pinion O' fast on the inner end of the shaft m. The main driving-shaft J drives the 25 shaft D through the gears K, K' and rotation is imparted by the pulley L to the pulley M through the belt l, and transmitted thence through the shaft m and gears O', O to the shaft C.
- 30 The shaft C carries the cam C' which reciprocates the thread-guide E and it has been determined that an improvement in the winding can be effected by varying the speed of the guide in relation to that of the drive-roll D' throughout the building of the cop. The usual practice in machines of this 35 class has been to maintain a constant ratio between the speed of the drive-roll and that of the thread-guide. With this arrangement, since the speed of rotation of the cop or package decreases as its diameter increases, a considerable change will take 40 place in the ratio between the speed of the cop and that of the guide. In other words, the cop will be rotated with a relatively 45 large number of turns during each traverse of the guide at the beginning of the winding and generally only a fraction of a turn to one traverse of the guide at the finish of the 50 winding. This results in a considerable disparity between the number of "winds" at the beginning and completion of the cop, and it is a well known fact that such a condition has inherent disadvantages which 55 result in defects in the winding and cause irregularities in the delivery of the yarn when the cop is unwound. When the yarn is wound from end to end of the cop with a relatively large number of turns it will hold 60 its place better than when wound with only a few turns. The coils are less liable to slip and become displaced when wound with a relatively slight pitch or lead; while, on the other hand, if the pitch or angle of the 65 coils is made too great there will be a tend-

ency for the yarn to pull in from the ends of the cop and this will cause irregularities on its surface, developing into ridges and bunches and finally resulting in a malformed package. Furthermore, when the 70 yarn has too quick a traverse across the cop at each revolution of the latter, the laying of the coils at the ends of traverse cannot be controlled so precisely and the yarn is liable to roll over the edges and draw across 75 the ends, making what are technically called "cobwebs". It is well known that these defects of "cobwebs" and other malformations in drum-wound cops are highly objectionable since they prevent free delivery of 80 the yarn in unwinding and otherwise lessen the commercial value of the package. As before stated, they are usually caused by the rapid decrease in the number of "winds" from start to finish of the cop and it has 85 been demonstrated that if the reduction in the number of "winds" is made less pronounced the cop is greatly improved. We have found that if the winding is started with say five-and-one-half or approximately 90 that number of "winds" and reduced to not less than about two-and-one-half "winds", a much more perfect cop can be produced. To effect this lessening of the disparity between the number of "winds" at the start 95 and finish of the cop and secure the preferred rate of change above specified we employ a mechanism for obtaining a differential ratio between the speeds of the drive-roll and thread-guide arranged as follows: 100

As before stated, the cam-shaft C which rotates the cam C' to reciprocate the thread-guide E is driven from the shaft D through the medium of the cone-pulleys L and M. To vary the ratio of speed between the 105 shafts C and D the belt l which connects the pulleys L and M is shifted longitudinally of the latter through the operation of a shipper-fork P, see Figs. 1 and 4. Preferably, the fork P is mounted on or formed as a part of an elongated bearing-hub p adapted to slide on a horizontal rod q projecting from the side of the frame B. The sliding movement of the fork P is effected through the operation of an arm or lever R pivoted at r on a bracket r' fastened to the base of the frame B. The upper end of the lever R is formed with a fork r'' which straddles a roll p' mounted on a screw p'' secured in a lug p''' on the hub p of the fork P. 115

The lever R is operated through means connecting it with the sliding carriage H which carries the winding-spindle G, as next described.

Referring now to Figs. 1, 2 and 4, the carriage H is formed with an arm h³ to which is attached the upper end of a vertical bar or rod S through the means of a screw or stud s. The rod S slides in a bearing b² formed as a part of an extension 125

of the frame B and moves upwardly with the carriage H as the winding-spindle G recedes from the drive-roll D' during the growth in diameter of the cop. The rod S has several functions: that of checking the downward movement of the carriage H through the operation of suitable dogging-mechanism engaging therewith, and also that of serving as an element of the 10 devices for controlling the position of the cop in relation to the drive-roll whereby the operation of the machine can be automatically arrested, all as described in our pending application herein first referred to. Its 15 purpose in connection with the speed-changing devices of the present invention is to operate the arm or lever R to slide the belt-shipper P outward along the pulleys L and M as the cop increases in diameter. Secured 20 to the lower end of the rod S is an arm or extension s² which projects through a slot b³ in the vertical member b⁴ of the frame B, see Fig. 2. The arm s² is formed with a downwardly-curved portion s³ to which is 25 pivotally attached the end of a link T by means of the screw t. The opposite end of the link T is pivotally secured to the upper end of the lever R by means of a screw t'. It will be seen that as the carriage H rises 30 with the increase in diameter of the cop being wound on the spindle G the end of the link T which is attached to the rod S will ride upwardly to rock the lever R outwardly away from the side of the frame B. This 35 movement of the lever R slides the shipper-fork P along the rod q and shifts the belt l toward the outer ends of the pulleys L and M. It is to be noted that the belt l is shifted with a gradually retarded rate of 40 movement for a purpose as later explained. That is to say, the first part of the movement of the lever R will be at a relatively fast rate, when the inner end of the link T is at the lower end of its throw, and as the 45 rod S rises the rate of movement of the lever will be gradually retarded until the link approaches a horizontal position. This arrangement for operating the belt-shipper with a retarded rate of movement in shifting 50 the belt from one end of the cone-pulleys to the other is a novel and essential feature of our invention as more fully pointed out hereinafter.

As the cop builds up on the winding-spindle with its mass becoming greater and greater its increasing weight will naturally add to its pressure on the drive-roll. Before the cop attains its maximum diameter this increased pressure is liable to cause the 55 ends to bulge, especially when soft yarn is being wound, and therefore it has been found advisable to correct this condition. With this object in view we employ a counterbalancing-device acting on the carriage H 60 which carries the winding-spindle G. Refer-

ring to Fig. 4, an arm U is pivotally mounted on a stud u screwed into the side of the gear-casing u' which incloses the gears K, K'. The hub of the arm U is formed with a sleeve u³ on which is mounted the hub of a second arm U'. The hub u⁴ of the arm U' is split at u⁵ and a binder-screw u⁶ serves to clamp it on the sleeve u³. The two members U, U' form virtually a bell-crank-lever, the arms of which can be adjusted in relation to each other by releasing the binder-screw u⁶. Extending from the end of the arm U is a rod w on which are mounted the compensating-weights W, W, etc., held in place by the collar w'. Connected to the outer end of the arm U' is a link u², the opposite end of which is fastened to the link T which, in turn, is connected with the arm s² of the vertical rod S.

Having now described the construction 85 and arrangement of the various mechanisms of our improved machine, the method of operation of the same will next be explained: Figs. 1 and 2 illustrate the machine with the

parts in the position they assume at the beginning of the winding. The carriage H is at the lower end of the rod H' and the winding-spindle G is in position with the surrounding cop-tube z bearing on the periphery of the drive-roll D'. The yarn y leads 95 up from its source of supply through a suitable tension-device, not here shown, and is threaded through the notch in the thread-guide E, whence it feeds to the winding-spindle G. With the carriage H in its lower-most position the arm s² on the rod S will be in such position that the bell-crank-lever U, U' will be held by the link u² with its arm U' upright. Under these conditions the weights W will have no effect on the carriage H, but the influence of gravity on the carriage and its connected parts will act to hold the cop-tube z in close contact with the drive-roll D'. In winding some varieties of material this pressure may be found too 100 great, however, and in such cases, then the arm U of the bell-crank-lever can be swung over to the right and adjusted to such a position, by means of the binder-screw u⁶, that the weights W will act through the link u² 105 to counterbalance a portion of the weight of the carriage and its parts. In most instances, however, the two arms U, U' will be adjusted in the relation shown in Fig. 1. Now, as the yarn builds up on the winding-spindle G and the carriage H is forced upwardly on the rod H' the link u² will rock the lever U, U' to move its arms clockwise. As the arm U swings to the right the weights W are carried over their center of support 110 and gradually they begin to exert a pressure tending to lift the carriage H. In this way by providing the proper number of weights W the increase in weight of the cop during 115 its growth can be accurately compensated 120

125 130

for and hence the pressure of the cop on the drive-roll will be maintained substantially uniform throughout the whole winding.

At the start of the winding, with the carriage H in its lowermost position as shown in Fig. 1, the link T will be in such position that the lever R will be rocked to the left and the shipper-fork P will maintain the belt l at the left-hand end of the pulleys L and M. As before stated, the shaft D is rotated from the driving-shaft J at a constant rate of speed. Now, with the belt l at the larger end of the cone-pulley L and driving therefrom, to the smaller end of the pulley M the latter will be rotated at its maximum speed. Consequently, the cam-shaft C which is driven from the pulley M, and the cam C' rotated therewith, will have a maximum speed at the start of the winding corresponding to the relatively fast speed of the winding-spindle when the diameter of the cop is at its minimum. As before mentioned, we have determined that the winding can be performed to the best advantage by starting the cop with about five-and-one-half revolutions of the winding-spindle to one traverse of the guide, and by finishing the cop with about two-and-one-half "winds", so that the cone-pulleys L, M and gears O, O' are preferably proportioned to give this result. One peculiar feature of the change in wind during the growth of the cop is that the variation is much more rapid at the small diameter than at a relatively large one. That is to say, the wind changes very rapidly at the beginning of the cop when its diameter is relatively small, while after the cop reaches say about one-half of its growth the variation in the wind is much less marked. For this reason it has been found advisable to adapt the speed-changing mechanism of the machine to act rapidly at first, and to be gradually retarded toward the end, so as to be somewhat more nearly proportionate to the quick change in speed-ratio between the cop and drive-roll. To accomplish this purpose the operation of the link T on the lever R is so timed that the belt-shipper P will be moved outwardly along the pulleys L and M very rapidly at first and more slowly toward the last. In this way the speed of the thread-guide E operated from the cam C' is made to agree more proportionately with the change in speed of the cop, although an exact proportion in this respect is not necessary.

By changing the speed-ratio between the drive-roll and thread-guide in this manner it is possible to so regulate the number of "winds" in proportion to the diameter of the cop that the pitch or angle of the coils or turns in the winding will remain substantially the same from start to finish. In other words, the coils of yarn will be laid on the surface of the cop with substantially

the same pitch or angle at all diameters throughout the winding. Through this improved method of regulating the "wind" the disposition of the coils is kept more uniform and regular and therefore the package is much superior both in appearance and in its capacity for free delivery of the yarn in unwinding. Furthermore, the changes in the number of winds at different stages of the winding are so few that there is less tendency for the coils of yarn to crowd together or "pile", even if no special means are employed for breaking up the "ribbon-wind".

We are aware that it has heretofore been proposed in winding machines to regulate the speed-ratio between the driving-drum and traverse-guide by means of a shiftable belt operating on cone-pulleys. In the present invention, however, we employ a different arrangement of means for this purpose and one so arranged that the ratio of change can be adjusted more nearly in proportion to the variation in speed of rotation of the cop. For this reason our improved machine is better adapted for winding fine yarn or thread in commercial packages suitable for a wide variety of uses in the textile art.

Our invention also provides means for relieving the increased pressure of the cop on the guide-roll consequent upon the increase in weight of the growing yarn-mass, as previously described; and hence the product is improved in this respect because irregularities and malformations in the winding are practically eliminated.

Various modifications might be made in the form and structure of the mechanism of our machine without departing from the spirit or scope of the invention; therefore, without limiting ourselves to the exact construction shown and described,

What we claim is:—

1. In a winding machine, the combination with a winding-spindle, of a drive-roll for rotating the cop wound on the spindle, a carriage for supporting the spindle to adapt it to recede from the drive-roll as the cop increases in diameter, a thread-guide, means to traverse the guide, oppositely-arranged cone-pulleys connecting the traverse-means with the drive-roll, a belt connecting said pulleys, a lever for shifting the belt along the pulleys, and a link connecting said lever to be operated from the carriage to cause the belt to be shifted on the pulleys with a gradually retarded rate of movement as the winding-spindle recedes from the drive-roll.

2. In a winding machine, the combination with a winding-spindle, of a drive-roll for rotating the cop, a sliding carriage for supporting the spindle to adapt it to recede from the drive-roll as the cop increases in diameter, a thread-guide, means to traverse the guide, oppositely-arranged cone-pulleys

- connecting the traverse-means with the drive-roll, a belt connecting said pulleys, a shipper-fork for shifting the belt along the pulleys, a pivoted lever for operating the 5 fork, a link connected with said lever, and means connecting said link with the carriage to cause the movement of the latter to swing the lever and operate the shipper-fork with a differential rate of movement.
- 10 3. In a winding machine, the combination with a winding-spindle, of a drive-roll for rotating the cop, a bearing for supporting the spindle to adapt it to recede from the drive-roll with the growth of the winding, 15 a thread-guide, means to traverse said guide, cone-pulleys connecting the drive-roll with the traverse-means, a belt connecting the cone-pulleys, a belt-shipper movable longitudinally of the axes of the pulleys to shift 20 the belt thereon, a rockable lever, means connecting the lever to the belt-shipper, a member connected with the spindle-bearing to be moved thereby away from the pivot of the belt-shipper lever, and a link connecting 25 said member with the lever to cause the latter to be rocked with a progressively retarded rate of movement.
4. In a winding machine, the combination with a winding-spindle, of a drive-roll for 30 rotating the cop wound on the spindle, means to support the spindle to adapt it to recede from the drive-roll as the cop increases in diameter, and means connected with the winding-spindle and operated from the 35 movement thereof to compensate for the increase in pressure of the cop on the drive-roll consequent upon the increase in weight of the yarn-mass during the growth in the winding.
- 40 5. In a winding machine, the combination with a drive-roll for rotating the cop, of a winding-spindle adapted to recede from said roll as the cop builds up thereon, a pivoted lever, weights on said lever, and means to 45 rock said lever from the movement of the winding-spindle to cause the weights to
- counteract the increased pressure of the cop on the drive-roll due to the increase in weight of its mass.
6. In a winding machine, the combination 50 with a drive-roll for rotating the cop, of a winding-spindle adapted to recede from said roll as the cop builds up thereon, a bell-crank-lever, weights on one arm of said lever, and means for connecting the other 55 arm of the lever with the winding-spindle whereby the movement of the latter will rock the lever to cause the weights to compensate for the increase in pressure of the cop on the drive-roll due to the increasing 60 weight of the yarn-mass.
7. In a winding machine, the combination with a drive-roll for rotating the cop, of a winding-spindle adapted to recede from the 65 roll as the cop builds up thereon, a bell-crank-lever connected with the spindle to be rocked from the movement of the latter, means to adjust the arms of the bell-crank-lever in relation to each other, and weights on one arm of the lever adapted to counter-balance the increase in pressure of the growing cop on the drive-roll when the lever is rocked.
8. In a winding machine, the combination with a drive-roll for rotating the cop, of a 70 winding-spindle on which the cop is wound, a bearing for supporting the spindle to adapt it to recede from the drive-roll as the cop increases in diameter, a bell-crank-lever, weights on one arm of said lever, and a link 75 connecting the other arm of the bell-crank-lever with the spindle-bearing to adapt the movement of the latter to rock the lever and relieve the pressure of the cop on the drive-roll throughout the winding.

In testimony whereof we affix our signatures in presence of two witnesses.
